UNITED STATES PATENT OFFICE.

FRANK L. BARROWS, OF MILWAUKEE, WISCONSIN.

METALLIC RAILWAY-TIE AND FASTENING THEREFOR.

SPECIFICATION forming part of Letters Patent No. 378,280, dated February 21, 1888.

Application filed April 5, 1887. Serial No. 233,712. (No model.)

To all whom it may concern:

Be it known that I, FRANK L. BARROWS, of Milwaukee, in the county of Milwaukee, and in the State of Wisconsin, have invented certain new and useful Improvements in Metallic Railway-Ties and Rail-Fastenings Therefor; and I do hereby declare that the following is a full, clear, and exact description thereof.

My invention relates to metallic railway-ties and rail-fastenings therefor, and will be fully set forth hereinafter, and pointed out in the claims.

In the drawings, Figure 1 is a plan view of one form of my device, showing the flanges of a rail secured in position thereby. Fig. 2 is a vertical longitudinal section of the parts shown in Fig. 1. Fig. 3 is a transverse section of another form of my device, taken on the line $\alpha\alpha$ of Fig. 4; and Fig. 4 is a plan view showing two forms of my invention.

A represents an ordinary railroad-rail, a being the web and $a'a'$ the flanges or base thereof, the tread not being shown in Figs. 1 and 4.

B represents my improved metallic tie, which preferably has a flat top and inclined flanges $b'b'$. Lips $b'b'$ are struck up at two points of each tie to receive the flanges a' of the rails, and these lips may be either of the form shown at the left or the right of Fig. 4, as preferred. Keepers b^2b^3 are formed on or from the tie adjacent to the lips, and these keepers may be either struck up, like the lips from the tie, in pairs, with an opening between, as shown in Fig. 1, or may be solidly raised or swaged out of or cast with the tie, as shown in Fig. 3 and to the right in Fig. 4.

C is the locking device, consisting of a flat strip of spring or elastic metal raised at one end c to conform to the shape of the rail-flange a^2 and bent down at the other end into a point or hook, c' , to enter a hole, d' , in the top of the tie, and thus securely keep the rails

in place on the ties, as shown, after the parts C have been pushed under the keepers b^2 , with the ends c bearing against the flanges a^2 , and also against the webs a in most cases.

In order to keep the ties B better in place on the road-bed, tongues D are punched from the tie-flanges $b'b$ and turned in at an angle thereto, and these tongues become embedded in the earth, gravel, &c., with which the ties are filled between their flanges, $d'd$ representing simply the holes in the flanges where the tongues D were punched out.

Having thus fully described my invention, what I claim as new, and desire to secure by Letters Patent, is—

1. A metallic tie having lips and keepers formed adjacent to each other on its upper surface, in combination with a locking device consisting of a strip bent at one end to conform to the shape of a rail-flange and having its other end bent down to enter a hole in said tie, substantially as set forth.

2. A metallic tie having lips and keepers struck or formed from or on its top surface and perforations beyond the keepers, in combination with elastic locking-strips bent at one end to conform to and bear against the rail-flanges and at the other end provided with hooks to enter the described perforations, substantially as set forth.

3. A metallic tie provided with side flanges having tongues struck therefrom and turned in at an angle thereto, substantially as set forth.

In testimony that I claim the foregoing I have hereunto set my hand, at Milwaukee, in the county of Milwaukee and State of Wisconsin, in the presence of two witnesses.

FRANK L. BARROWS.

Witnesses:

MAURICE F. FREAR,
N. E. OLIPHANT.
